DOOR OPERATION CONTROL

Cyrus W. Bassett, Port-au-Peck, N. J., assignor, by mesne assignments, to National Pneumatic Co., Inc., Boston, Mass., a corporation of Delaware

Application March 20, 1948, Serial No. 16,113

2 Claims. (Cl. 268—46)

1

This invention relates to the operation of doors and particularly to the control of a motor or engine for the application of operating power to a sliding type of door.

Sliding doors, as a rule, are more difficult to open than are doors which swing on hinges. There are many reasons why this is so, but one important reason is that a person walking directly toward a door, with the intention of opening it and continuing his course in the same line, directly through and beyond the door opening, finds it much easier to exert a direct pressure, or "push," upon the surface of the door, than to exert a side-wise pull such as is required to initiate the opening motion of a sliding door.

The present invention provides a novel method and means of operation of a sliding door, which novel method permits use of the easier "push" technique heretofore applicable to swing doors only, rather than the "side-wise pull" technique.

More specifically, the invention provides a power-operated slide type door having incorporated in the door itself a novel control mechanism for energizing the power unit in the proper manner to cause application of door opening force to the door; the said control mechanism being operable by applying a slight "push" against either one of two panels provided on opposite faces of the door, thus permitting use of the power control mechanism by persons approaching the door from either of two opposite directions.

A control of the character herein disclosed is particularly desirable for multiple car vehicles (railway trains and the like) where there is considerable traffic from one car to another by way of inter-connecting doors at the adjacent car ends. Such traffic, of course, flows in both directions, hence a control mechanism such as herein disclosed, being operable by persons approaching in either direction simply by applying slight pressure to a conspicuous panel on the door surface, is of great utility. The invention is equally useful in other situations, of course, and in fact wherever doors of the sliding type are employed.

An object of the invention, therefore, is to provide a door having incorporated therein control means for its own operation, said control means being operable by slight pressure applied to either face of the door.

A second object is to provide control means of novel construction permitting energization of a door opening instrumentality in response to relative motion between a panel mounted on

the door, and the door itself; such relative motion being brought about by any slight pressure applied to any portion of the panel.

A third object is to provide control means of the character indicated, which control means is accessible for operation for the purpose of opening a slide-type door, but is not accessible for operation if the door happens to be in its fully open position; additional control means being provided to move the door back to the closed position.

A fourth object is to provide a novel combination of switch operating elements, including a pair of plates, or panels, each normally aligned with one door surface, and normally separated circuit-closing members interposed between said panels and engageable in response to a shifting of either panel, to even a slight degree, from its normal disposition in relation to the other.

Other objects and features of the invention will become apparent upon examination of the following further description, to be read with reference to the accompanying drawings wherein:

Fig. 1 shows a slide-type door and a receiving wall-pocket; the door including switch operating push-plates, or panels, incorporating the invention;

Fig. 2 shows the manner in which the wall-pocket conceals the push-plates and thereby prevents operation thereof when the door is in the fully open position;

Fig. 3 is a front elevation view of one of the push-plates;

Fig. 4 is a side elevation view, showing both push-plates in assembled relationship on the door;

Fig. 5 is a sectional view along line 5—5 of Fig. 3;

Fig. 6 is an elevation view of the switch mechanism attached to the push-plate of Fig. 3;

Fig. 7 is a sectional view along line 7—7 of Fig. 6;

Fig. 8 is a sectional view along line 8—8 of Fig. 6;

Fig. 9 is a sectional view along line 9—9 of Fig. 6; and

Fig. 10 is a schematic diagram of the complete apparatus.

The two push-plates 15, 16 are yieldingly mounted in a cut-out portion of slide door 17, the latter carrying hollow rectangular frames 18, 19 attached to opposite faces of the door, about the edges of the cut-out portion, by screws 21, 22 (see Figs. 3 and 4) lugs 23, 24 on

the plates 15, 16, respectively, receive the end portions of shouldered studs 26, 27, 28, and 29, there being one at each end of the four corners of the aligned plates. Springs 31 surrounding the studs urge the plates 15 and 16 away from each other, to the extent permitted by the fixed spacing of the retaining frames 18 and 19, respectively; and in these outermost positions (see Fig. 4) the outer surfaces of the plates are disposed slightly in advance of the main surfaces of the door, designated by numerals 32 and 33 in Fig. 4, and similarly in Figs. 1 and 2. The distance from plate to plate, however, does not exceed the door width sufficiently to create interference with the walls 36, 37 (Figs. 1 and 2) between which the door, including the plates 15 and 16, is received when it slides to the fully open position shown in Fig. 2.

Plate 15 carries the switch assembly shown in greater detail in Figs. 6 to 9, and plate 16 carries adjustably a screw 41 engageable with a button 42 of the switch assembly when either plate 15 or plate 16 is pressed toward the other; the spacing being such that a very slight movement of either plate (induced by touching the plate at any region thereof) suffices to produce engagement of parts 41 and 42. Such engagement, and the resultant pressure of diaphragm 43 upon switch finger 44 (Fig. 7) completes an electric circuit from current source 45 (Fig. 10) to the valve control relay 46 of door operating engine 47, the circuit completion occurring at the switch contacts 48, 49 of Fig. 7, the former being secured to switch finger 44 and the latter to terminal strip 51. Leads 52, 53 (Fig. 10) extend from terminals 54, 55 respectively, the latter being the points of anchorage of switch finger 44 and terminal strip 51, respectively. Thus the circuit runs from source 45 by way of lead 52 to terminal 54, thence across contacts 48 and 49 to terminal 51, 55 and by way of lead 53 to the valve operating relay 46, and thence to ground.

Energization of relay 46, through the circuit just traced, performs two functions: first it establishes a holding circuit for the relay by way of holding contact 58, and secondly, it completes a circuit through contact 59 to energize solenoid 56 of the valve assembly 57.

Energization of solenoid 56 causes valve 57 to function, whereupon engine 47 operates to move the door from the closed position (Fig. 1) to the open position (Fig. 2), in which, latter position, the push plates are concealed within the walls of the door pockets and therefore are inaccessible for manual operation; however, manual operation to re-close the door is not required, as the closing operation is automatic, as will now be pointed out.

Automatic closing of the door is provided by inserting in line 61 (Fig. 10) a pair of contacts normally bridged by a switch 62, which switch 62 is opened by a striker 63 on door actuating lever 64, as the door reaches fully open position. Opening of the switch 62 de-energizes both the relay 46 and the solenoid 56, whereupon valve 57 reverses its position and causes engine 47 to operate in the reverse direction, thus closing the door.

The door operating engine 47 is assumed to be of the well-known differential type, although any other preferred type may be substituted. As illustrated schematically in Fig. 10, the piston of larger effective area is in the left end of the unit, the piston of smaller effective area

being on the right. The two pistons are joined by a toothed rod (rack) meshing with a gear to be rotated thereby, the gear and lever being secured, one to the other, either directly or indirectly, so that the lever swings through an arc of approximately ninety degrees as the pistons travel from one extreme position to the other.

Engine 47 is normally supplied with pressure fluid at both ends, the valve 57 being so constructed that its exhaust port is normally blocked off, and communication between the left end of the unit and the supply line normally prevails through said valve; but upon energization of winding 56 this normal setting is reversed, and the left end of the cylinder is opened to exhaust through the valve exhaust port; the supply line being simultaneously blocked off. Meanwhile supply pressure continues in the right side of the unit and causes the piston assembly to move to the left, thus opening the door, as previously described. De-energization of the winding 56, by the automatic operation above described, restores the valve 57 to its normal setting and the resultant pressure differential in a rightward direction causes the piston assembly to return the door to the closed position.

I claim:

1. The combination, with a wall pocket, of a door slidable into said wall pocket, to clear a passageway, a door operating motor, means for controlling energization of said motor, in a direction to cause sliding movement of the door into said wall pocket, said means including a motor energizing circuit having a movable switch element therein, a pair of striker elements abutting said movable switch elements on opposite sides thereof, means for causing one or the other of said striker elements to exert circuit closing pressure upon said movable switch element, said last named means including a pair of flat plates carried on opposite surfaces of the door adjacent said striker elements, either of said flat plates being movable toward the other, to move said switch element to circuit-closing position in response to pressure applied to either face of the door; said flat plates being concealed within said wall pocket when the door reaches the limit of its motion in one direction, and means movable with the door operating motor to cause a reversal of the direction of power application and thereby return the door to its initial position, independently of any further actuation of either of said door plates.

2. The combination, with a wall pocket, of a door slidable into said wall pocket, to clear a passageway, a door operating motor, means for controlling energization of said motor, in a direction to cause sliding movement of the door into said wall pocket, said means including a motor energizing circuit having a movable switch element therein, a pair of striker elements abutting said movable switch elements on opposite sides thereof, and means for causing one or the other of said striker elements to exert circuit closing pressure upon said movable switch element, said last named means including a pair of flat plates carried on opposite surfaces of the door adjacent said striker elements, either of said flat plates being movable toward the other, to move said switch element to circuit-closing position in response to pressure applied to either face of the door; said flat plates being concealed within said

wall pocket when the door reaches the limit of its motion in one direction.
